UNITED STATES PATENT OFFICE

LOUIS LARSON, OF LYNDEN, WASHINGTON

DIVIDER BAR ATTACHMENT FOR MOWERS

Application filed September 5, 1931. Serial No. 561,439.

This invention relates to divider bars for mowing machines, and more particularly to novel means through the medium of which a mowing machine having a divider board 5 may, after the removal of the board, be equipped with a divider bar.

The invention has for one of its objects to provide means of the character stated through the medium of which a divider bar may be applied to a sickle bar shoe, from which a divider board has been removed, without making any changes or alterations in the shoe, and through the medium of which the substitution of the divider bar for the divider board may be made readily by an unskilled person.

The invention has for a further object to provide means of the character stated which will support the divider bar in a normal position inclining upwardly and rearwardly from the sickle bar shoe, which will permit the divider bar to swing for a limited distance upwardly from its normal position, and which will permit the normal position of the divider bar to be raised or lowered to adapt it for use in tall and short grass.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of a divider bar secured, in accordance with my invention, to a sickle bar shoe.

Figure 2 is a view partly in elevation and partly in vertical section of a fragmentary portion of the divider bar and the means for securing the divider bar to the shoe.

Figure 3 is a top plan view of a fragmentary portion of the divider bar and the means for securing it to the shoe, and

Figure 4 is a sectional view taken on the plane indicated by the line 4—4 of Figure 2.

Referring in detail to the drawing, 1 designates the shoe of a mower sickle bar. The shoe 1 which is rigidly secured to the outer end of the sickle bar, and which is of well-known construction, is provided with an

opening 2 and a lug 3 to adapt it for the application thereto of the usual divider board which is supplanted by my invention. The bolt by which the divider board was secured to the shoe 1 passed through the opening 2, and the divider board contacted with the lug 3, which is located at the outer side of the shoe above and forwardly of the opening, to limit its downward swinging movement on the bolt.

My invention comprehends the provision of a casting or block 4 through the medium of which a divider bar 5 of well-known formation may be secured to the shoe 1. The block 4 is of substantial elongated rectangular formation in elevation, and is provided near one end thereof with an opening 6 for the reception of a bolt 7 by which it is secured to the shoe 1. The bolt 7 passes through the opening 2 of the shoe 1, and the block 4 is located at the outer side of the shoe with the greater portion thereof extending rearwardly from the bolt.

The block 4 is provided at its upper front corner with a forwardly directed extension or lug 8 which contacts with the underside of the lug 3 to support the block in an upwardly and rearwardly inclined position on the shoe 1.

The block 4 is provided at its inner side with a recess 9 which is closed at its front and open at its rear end. The recess 9 is provided for the reception of the front end portion of the divider bar 5, and the rear end of the divider bar is provided with an eye 10 for the reception of the bolt 7. The bolt 7 connects the divider bar 5 to the shoe 1 for swinging movement about a horizontal axis with respect to the shoe and the block 4. The upper and lower flanges 11 and 12 of the block 4 limit the swinging movement of the divider bar 5 with respect to the block, and the downward swinging movement of the divider bar with respect to the shoe 1 is limited by the block. The block 4 is supported in an upwardly and rearwardly inclined position in the shoe 1 by the lugs 3 and 8, and the block supports the divider bar 5 in an upwardly and rearwardly inclined position with respect to the shoe. When the divider bar 5 is

in contact with the lower flange 12 of the block 4, it is in its normal position with respect to the block, and this position of the divider bar may be varied through the medium 5 of a set screw 13 which passes through the flange and contacts with the lower side of the divider bar. The set screw 13 is provided with a nut 14 which contacts with the flange 12 to hold the bolt against accidental turning.

In practice, when it is desired to substitute the divider bar 5 for the divider board of a mowing machine, it is only necessary to remove the divider board from the sickle bar 15 shoe and secure the divider bar and block 4 to the shoe. This may be done by merely passing the bolt 7 through the opening 2 of the shoe and by applying a nut 15, to the outer end of the bolt. The application of 20 the block 4 to the shoe positions the lug 8 of the block below the lug 3 of the shoe, and the combined weights of the block and divider bar 5 normally hold the lug of the block in contact with the lug of the shoe, with the result 25 that the block and divider bar are supported in an upwardly and rearwardly inclined position on the shoe. The block 4 and divider bar 5 are rockably connected to the shoe by the bolt 7 for simultaneous swinging 30 movement upwardly from and backwardly to their normal positions, the normal position of the block being determined by the lug 3, and the normal position of the divider bar being determined by the flange 12 or set 35 screw 13, which latter permits the normal position of the divider bar to be varied, so as to adapt it for use in tall and short grass.

From the foregoing description, taken in connection with the accompanying drawing, 40 it will be understood that the invention permits a divider bar to be readily substituted for a divider board, which latter cannot be successfully used in heavy grass, and that the invention is simple, durable and capable 45 of being manufactured and sold at a comparatively low cost.

While I have described the principle of the invention, together with the structure which I now consider the preferred embodiment thereof, it is to be understood that the structure shown is merely illustrative and that such changes may be made, when desired, as fall within the scope of the invention as claimed.

55 What is claimed is:—

1. In combination, a sickle bar shoe having a lug and an opening located below and rearwardly of the lug, a bolt passing through the opening, a block connected to and extending 60 rearwardly from the bolt and having a lug contacting with said first lug, a divider bar connected to the bolt and supported by the block, and means for adjusting the divider bar relative to the block.

65 2. In combination, a sickle bar shoe hav-

ing a lug and an opening located below and rearwardly of the lug, a bolt passing through the opening, a block connected to and extending rearwardly from the bolt and having a lug contacting with said first lug, a divider 70 bar pivoted to the bolt, and a set screw carried by the block and contacting with the lower side of the bar and constituting means by which the bar may be adjusted with respect to the block.

3. In combination, a sickle bar shoe having a lug and an opening located below and rearwardly of the lug, a bolt passing through the opening, a block pivoted on the bolt and extending rearwardly therefrom and provided 80 with a lug contacting with said first lug, the block being provided with a recess opening out through one side and the rear end thereof, a divider bar having an end thereof positioned in the recess and pivoted to the bolt, 85 and a set screw carried by the block and contacting with the lower side of the bar and constituting means by which the normal angular position of the bar with respect to the block may be varied.

4. Means for securing a divider bar to a sickle bar shoe having a lug and an opening comprising a block, a bolt carried by the block and passing through said opening, a lug carried by the block and contacting with 90 said first lug, a divider bar pivoted to the bolt, and means adjustably carried by the block and contacting with the rear side of the bar for adjusting the bar relative to the block.

In testimony whereof I hereunto affix my signature.

LOUIS LARSON.
